United States Patent Office.

L. R. WITHERELL, OF GALESBURG, ILLINOIS, ASSIGNOR TO HIM SELF AND CHARLES F. CALKINS, OF SAME PLACE.

Letters Patent No. 95,400, dated September 28, 1869.

IMPROVED DISH-WASHING MACHINE.

The Schedule referred to in these Letters Patent and making part of the same.

To all whom it may concern:

Be it known that I, L. R. WITHERELL, of the city of Galesburg, county of Knox, and State of Illinois, have invented certain new and useful Improvements in Dish-Washing Machines; and I do hereby declare the following to be a full, clear, and exact description of the same, reference being had to the accompanying drawings, making a portion of this specification, in which—

Figure 1 is a longitudinal vertical sectional view.

Figure 2 is a cross-section.

Figure 3 is a view of one end of the dish-rack, showing the manner of hanging it.

Figure 4 is a view of the other end of the dish-rack, showing the manner of hanging it.

Similar letters of reference indicate corresponding parts in all of the figures.

The nature of this invention relates to improvements in machinery for washing dishes, cups, and other table-ware; and

The invention consists in a stationary rack for holding dishes, cups, saucers, or other like articles, arranged within a revolving box, containing the water for washing the dishes, and strips or wings in the corners of said box for the purpose of dashing the water among the dishes, when the box is rotated; the whole being supported on a suitable frame by means of the crank-shaft and a spout, said spout so arranged as to hold the rack stationary, while it allows at the same time the outer box to be revolved on it as a bearing, serving at the same time to allow of the free escape of steam or gas while it holds the water.

Said crank is so arranged that it may be used to rotate the outer box, while it serves as a support for the stationary rack.

To enable others to understand the construction and operation of my invention, I will proceed to describe it with reference to the drawings.

Letters H, I, and K, represent the frame for supporting the machine.

H H represent two uprights supported on the feet K K, and braced by the boards I I.

A represents the box, of which B is the lid, hinged at G; and provided with straps O O across it.

E represents two arms, pivoted to the piece m, on the side of the box A.

F represents a hand-lever, pivoted between the upper ends of the arms E, so as to form an eccentric at the pivoted end.

D represents an arm, secured to the lid B, and projecting between the arms E, so that the eccentric lever may have a bearing thereon when thrown forward, and tighten the lid B to the box A, and when thrown into the position shown by the red line, F', the lid will be released.

X X" X" represent projecting strips, secured in the corners of the box A, the strips X" X" being attached to the lid B.

T is a crank, having bearings in the upright H, and projecting through the side of the box A, and attached thereto, may be used to rotate the said box A; the other end of the box A having a bearing on the spout W, which is held securely to the upright H by means of the strap y and block v.

L represents a semi-cylindrical rack or case, its ends formed of wood or metal, and its cylindrical surface formed of wire gauze.

R represents wire rods, arranged transversely on the top of the rack L.

P represents a bar along the lower surface of the rack L, and supporting the spikes or pins N.

The dishes to be washed are stood on edge between the rods R, and are held in place at the lower end by the pins N.

A part of the rods R are arranged in a frame, as shown by the red line s, so they may be raised, and the smaller articles, such as cups, saucers, &c., be placed inside of the rack.

One end of the rack L is supported on the end of the spout W, as shown fully at fig. 3, the shape of the bearing W preventing the rack from turning, and the shape of the bearing Z allowing the rack to be lifted out of the box A, when desired.

The other end of the rack L is supported on the end of the crank T, as shown at fig. 4, in a manner to allow the end of the crank free motion, without turning the rack, the bearings d also allowing the rack L to be lifted by the hand-holds a from the box A.

J represents a lever, pivoted at its lower end between the braces I, and when thrown up, as shown in the drawings, will hold the box A horizontal, or inclined, as shown by the red line p, fig. 2, in which position the water may be drawn off through the hole g, which hole is closed by the stop f, pivoted on the side of the box A.

While the box A is being revolved, the lever J may be dropped to the position shown by the red line.

The manner of operating my machine is as follows:

The dishes being placed in the rack L, as before described, hot water is poured into the box A, a few inches in depth.

The lid B is then closed tightly, and the box A revolved by the crank T, the water being thrown, by means of the wings X, against all surfaces of the dishes, and with a force proportioned to the velocity of revolution of the box A.

The steam, &c., escaping by means of the opening V in the tube W, said opening V being so situated

in the under side of the tube W as to prevent the water escaping.

Having thus described my invention,

What I claim as new, and desire to secure by Letters Patent, is—

The stationary rack L, constructed as described, in combination with box A, wings X X", spout W, crank T, and frame H, I, and K, when arranged to

operate as herein described for the purpose specified.

Signed at Galesburg, Illinois, this 21st day of June, 1869.

L. R. WITHERELL.
